UNITED STATES PATENT OFFICE.

JAMES M. CONNER, OF NEW YORK, N. Y.

DESIGN FOR A FONT OF PRINTING-TYPES.

SPECIFICATION forming part of Design No. 11,642, dated February 3, 1880.

Application filed January 9, 1880. Term of patent 7 years.

To all whom it may concern:

Be it known that I, JAMES M. CONNER, of the city, county, and State of New York, have invented and produced a new and original 5 Design for a Font of Printing-Types, of which the following is a specification.

The nature of my design is clearly shown in the accompanying typographic impression, to which reference is made; and it consists of 10 an ornamental letter shaded upon the right and bottom by a heavy line succeeded by a lighter one.

The up-and-down portions of all the letters are concaved upon the right and left and above 15 and below the central lines of the letters, and the horizontal portions of the letters at the top and bottom are concaved and provided with the central-pointed ornamentations, as shown.

20 The up-and-down portions of the letters, except the C, G, J, O, Q, and U, are continued at the top and bottom, and form terminations having inclined sides. In the J and U these occur at the top, and the upper and lower 25 terminations of the C and G upon the right are so designed. The faces of the letters are ornamented by the heavy triangular-shaped figures, as shown.

In the letters B, C, D, E, G, O, Q, and S the inner, upper, and lower horizontal portions of the letters are concaved and provided with a central triangular ornamentation at top and bottom, and in the letters F, R, and P this ornamentation occurs only in the upper portions of the letters. 30

The character of the design is preserved in the symbols, figures, and lower-case, the inner triangular ornamentation occurring at the bottom upon the left in the symbol &. 35

In the figures 2, 3, 5, 6, 9, and 0 the central 40 triangular ornamentations occur at the top and bottom, and in the lower-case the disconnected portions of the i and j are formed of squares having curved sides, in the centers of which are placed the heavy dots, as shown. 45

Having now set forth my invention, what I claim as new is—

The design for a font of printing-types, as shown and described.

JAMES M. CONNER.

In presence of—

W.M. C. CONNER, Jr.,
GEO. W. WOOD.
